^{BY} ATTORNEY

UNITED STATES PATENT OFFICE

JOHN J. CAIN, OF BAYONNE, NEW JERSEY

METHOD OF MAKING METAL BARRELS AND THE LIKE

Application filed June 27, 1928. Serial No. 288,565.

This invention relates to improvements in a method of making metal barrels and the like and the principal object is the provision of a method whereby metallic containers such as barrels may be readily made on a production basis from pre-formed or pre-shaped metal and which will be strong and secure in construction and capable of standing extended usage and rough handling.

10 A further object of this invention is the provision of a process by which a sheet of metal is pre-shaped so as to be convex longitudinally thereof and also having a groove or grooves formed longitudinally thereon, this 15 pre-shaped metallic sheet being then cut into lengths, the lengths being bent into cylindrical form so as to form the body of the barrel, such as disclosed in my copending application for patent on metallic drum barrel or 20 container, Serial No. 229,310 filed October 28, 1927.

To the accomplishment of the foregoing and such other objects as may hereinafter appear, this invention consists in the process 25 or method hereinafter described and then sought to be defined in the appended claims, reference being had to the accompanying drawings for illustrative purposes only.

In the drawings,

30 Fig. 1 represents a perspective view of a small portion of a metallic sheet after it has been rolled or otherwise shaped in one step of my new method or process, it being understood that the concavity shown and the 35 grooves shown extend the full length of the sheet.

Fig. 2 represents a perspective view of the body of a barrel formed of one piece construction of suitable length cut from the pre-shaped sheet shown in Fig. 1, and bent into cylindrical form.

40 Fig. 3 represents a perspective view of the body of a barrel formed in two parts cut from the pre-formed metal sheet of Fig. 1 and bent 45 into cylindrical form to complement each other to form the barrel body.

I am aware that there have been numerous attempts to make metallic barrels and similar containers. For the most part these structures have been composed of a large number

of parts which have to be assembled and secured together involving complication of work and numerous joints and fastening means with the resultant disadvantages of the possibility of breakage and disassembling, 55 and weakness in structure. It has also been proposed to make metallic barrels of sheets of material rolled into cylindrical form and then to shape these barrels with the normal barrel bilge, but so far as I am aware, this has never 60 been satisfactorily done in such a way as to be commercially practicable in making a metallic barrel of general utility.

In my new method or process the resultant barrel is composed of a minimum number of 65 parts, the bilge being formed in the sheet of metal when the same is rolled. In other words, the metallic sheet which forms the body of the barrel is pre-shaped with the characteristic barrel bilge during the rolling 70 operation of the sheet of metal so as to prevent the introduction of flaws, inequalities and breaks into the sheet metal, which occur when the shaping operation is attempted after the sheet of metal is originally rolled.

75 In other words, in order to express this idea a little more clearly, when the sheet metal is being rolled it is of course being expanded and stretched in all directions and during this operation, in my method or process, the sheet 80 1 is so rolled as to form the longitudinally extending convex portion 2 throughout the full length thereof, see Fig. 1. It is this convex portion which forms the characteristic barrel bilge when the barrel is assembled. At the 85 same time, or rather during the same operation, I also form the longitudinally extending grooves 3 in the sheet of metal, which when the barrel body is assembled, receive the heads of the barrel, as is well understood. 90 It is, therefore, seen that all shaping of the metal which requires any flow or real strain of the metal is accomplished during the rolling operation, which insures that the barrel body will be at its maximum strength and 95 without flaws or breaks, when assembled.

The next step of my method involves the cutting of the pre-shaped or pre-formed metal sheet into suitable lengths. It is to be understood that by having the metal sheet pre- 100

shaped, the barrel body may be formed of one length or portion of metal, as indicated in Fig. 2, or it may be formed of two lengths, as indicated in Fig. 3. This is especially to be noted in contradistinction to such metallic barrels as use a large number of parts or staves similar to the standard wooden barrel, in that respect.

In making metal barrels in which the body is composed of a single length of the pre-shaped metal sheet, see Fig. 2, this sheet is cut into portions of such length that they may be bent or curved into a complete cylinder. Ordinarily, with a normal bilged barrel, the length is cut so as to have a longer central part which is to form the bilge, so that in bending, the edges will meet and the result will be a bilged barrel. If a larger or smaller bilge is desired, different shaped lengths must be cut from the sheet as will be obvious to one skilled in the art. This may be done on various forms of apparatus, most of which are quite simple and as the operation involves no stretching or straining of the metal, no damage or weakening of the body of the barrel will result. When bent into the cylindrical form the body of the barrel will have the appearance of Fig. 2, wherein 4 represents the body as a whole; 5 the joining seam where the ends of the length of the pre-shaped metallic sheet may be joined or fastened by any suitable means, if necessary; 6 the characteristic barrel bilge or bulge; and 7 the grooves formed internally thereof near the top and bottom to receive the heads of the barrel, as is well understood.

In the barrel shown in Fig. 3 the body is formed of two lengths of the pre-shaped metal sheet and in this case each length is bent into a semi-cylindrical form, so that the two parts complement each other to form the completed barrel body. Otherwise, the structure and the operation are the same.

Of course it is to be understood that barrel bodies may be formed by this method or process having a greater number of parts than those shown, but one of the advantages of using this method or process resides in the fact that the barrel body may be composed of a minimum number of parts and be of substantially integral construction with the resultant maximum factor of safety.

It is obvious that this process is advantageous in that metal sheets constructed in accordance therewith may be conveniently nested for shipping and storing as they are made in standard and complementary sizes. The matter of assembling them is simple as the parts being standard will readily fit each other. The barrel when assembled, will be strong in construction by virtue of its formation and due to the fact that no flaws or weaknesses are developed in the material during the making of the same.

What I claim is:

1. The method or process of making metal barrels and the like which includes pre-shaping a sheet of metal during the rolling thereof to form a longitudinally extending convex portion or bilge therein, cutting said pre-shaped metal sheet into lengths and bending said lengths into cylindrical shape so as to form a barrel body. 70

2. The method or process of making metal barrels and the like including the step of pre-shaping a sheet of metal while it is being rolled to form a convex portion or bulge therein, cutting said metal sheet into lengths and bending said lengths into cylindrical shape 75 80 to form the body of the barrel.

3. The method or process of making metal barrels and the like including pre-shaping a sheet of metal during the rolling thereof so as to provide a convex portion or bulge therein and also forming at the same time, a plurality of grooves therein, cutting said metallic sheet into lengths and bending said lengths into cylindrical shape, the convex portion forming the bilge of the barrel body and the 85 90 grooves being adapted to receive the heads of the barrel.

4. The method or process of making metallic barrels and the like including pre-shaping a metal sheet during the rolling thereof to 95 form a convex portion extending longitudinally thereof and a plurality of grooves extending longitudinally thereof and near its edges, cutting said pre-shaped metallic sheet into lengths and bending said lengths to form 100 the barrel body, said convex portion forming the bilge and said grooves being adapted to receive the heads of the barrel.

5. The method or process of making metal barrels and the like which comprises rolling 105 a sheet of metal with a convex intermediate portion, the side edge portions being flat, and at the same time rolling grooves into said side edge portions, cutting said pre-shaped sheet of material into lengths and bending 110 said lengths into cylindrical form to provide a barrel body.

6. The method or process of making metallic barrels and the like, including preshaping a sheet of metal during the rolling thereof so as to provide a convex portion or bulge therein and also forming at the same time a plurality of grooves therein, cutting a suitable length out of said metallic sheet and bending said length into cylindrical shape, 115 the convex portion forming the bilge of the barrel body and the grooves being adapted to receive the heads of the barrel. 120

7. The method or process of making metallic barrels and the like, including preshaping a sheet of metal during the rolling thereof so as to provide a convex portion or bulge therein and also forming at the same time a groove therein, cutting said metallic sheet 125 130 to form a sheet of the desired dimensions, and

bending said sheet into cylindrical shape, the convex portion forming the bilge of the barrel body and the groove being adapted to receive a head of the barrel.

8. The method or process of making metallic barrels and the like, including preshaping a sheet of metal so as to provide a convex portion or bulge therein and also forming at the same time a groove therein, cutting a suitable length out of said metallic sheet and bending said length into cylindrical shape, the convex portion forming the bilge of the barrel body and the groove being adapted to receive a head of the barrel.

9. The method or process of making metallic barrels and the like, including preshaping a sheet of metal so as to provide a convex portion or bulge therein and also forming at the same time a plurality of grooves therein, cutting said metallic sheets into lengths and bending said lengths into cylindrical shape, the convex portion forming the bilge of the barrel body and the grooves being adapted to receive the heads of the barrel.

In testimony that I claim the foregoing, I have hereunto set my hand this 11th day of June, 1928.

JOHN J. CAIN.
